ATTORNEY

UNITED STATES PATENT OFFICE.

THEODOSIUS ALBERT WILLIAMS, OF BATTLE GROUND, WASHINGTON.

DESIGN FOR A SPOON-HANDLE.

58,520.

Specification for Design.

Patented July 26, 1921.

Application filed March 29, 1919. Serial No. 286,179. Term of patent 14 years.

To all whom it may concern:

Be it known that I, THEODOSIUS ALBERT WILLIAMS, a subject of the King of Great Britain, and residing at Battle Ground, in the county of Clarke and State of Washington, have invented a new, original, and ornamental Design for Spoon-Handles, of which the following is a specification, reference being had to the accompanying drawing, forming part thereof.

The figure is a side view of a spoon with

especial reference to the handle which shows on the underside, near the end, and where it is of no inconvenience to the user, an ornamental ridge across the width of the handle, while the end beyond the ridge is slightly thickened and turns upwardly with a graceful curve.

I claim:

The ornamental design for a spoon-handle as shown.

THEODOSIUS ALBERT WILLIAMS.
